Primary Examiner — Nathan M Johnston(57) **CLAIM**

The ornamental design for a medical needle device, as shown and described.

DESCRIPTION

FIG. 1.1 is a left perspective front view of the medical needle device showing the new design.

FIG. 1.2 is a left perspective rear view of the medical needle device in FIG. 1.1.

FIG. 1.3 is a right side view of the medical needle device in FIG. 1.1.

FIG. 1.4 is a left side view of the medical needle device in FIG. 1.1.

FIG. 1.5 is a bottom view of the medical needle device in FIG. 1.1.

FIG. 1.6 is a top view of the medical needle device in FIG. 1.1.

FIG. 1.7 is a front view of the medical needle device in FIG. 1.1.

FIG. 1.8 is a rear view of the medical needle device in FIG. 1.1.

The dashed lines in the figures illustrate the portions of the design that form no part of the claimed design. The dash dot lines depict environmental subject matter only and form no
